UNITED STATES PATENT OFFICE.

JAMES M. WALSH, OF MILWAUKEE, WISCONSIN, ASSIGNOR TO WALSH HARNESS COMPANY, OF WILMINGTON, DELAWARE, A CORPORATION OF DELAWARE.

NECK-YOKE FASTENING.

1,318,420.

Specification of Letters Patent.

Patented Oct. 14, 1919.

Application filed December 24, 1915. Serial No. 68,516.

To all whom it may concern:

Be it known that I, JAMES M. WALSH, a citizen of the United States, residing at Milwaukee, in the county of Milwaukee and State of Wisconsin, have invented certain new and useful Improvements in Neck-Yoke Fastenings, of which the following is a specification, reference being had to the accompanying drawing, forming a part thereof.

This invention relates to fastenings for detachably connecting the breast straps of double harness with neck yokes.

The main objects of the invention are to prevent accidental disengagement of such fastenings; to facilitate manipulation thereof; to avoid mutilation, wear and weakening of the straps connected therewith; and generally to improve the construction and operation of devices of this class.

It consists in the construction, arrangement and combination of parts as herein-after particularly described and pointed out in the claims.

25 In the accompanying drawing like characters designate the same parts in the several figures.

Figure 1 is a front elevation of the fastening in connection with portions of a breast strap and neck yoke; Fig. 2 is a side elevation of the fastening as viewed from the right relative to Fig. 1; and Fig. 3 is a horizontal section and plan view on the line 3—3, Fig. 2.

30 The fastening comprises a hanger through which the breast strap *a* is looped and freely movable; a member *b*, articulated with the hanger and having an upwardly bent hook *c* for detachable engagement with a neck yoke ring or eye *e*, and means, such as an upwardly bent hook *d*, for detachable engagement with a connecting and locking member, such as an eye *g*, to which the martingale *f* is attached.

35 The breast strap hanger consists of a metal loop *h*, formed at the ends with inwardly projecting pintles *i*, and with a central downwardly and sharply curved round bearing portion *j*, and a spool *k* provided with a metal bushing *l*, which is mounted on the pintles *i*. The spool *k*, which is made of wood or similar material, is formed with end flanges to guide the breast strap *a* thereon and prevent its edges from chafing and 40 wearing against the sides of the hanger loop

h. The bushing *l* is also preferably flanged at the ends to hold the spool *k*, which is made of softer material, out of contact with the sides of the hanger loop *h*.

To assemble the parts of the hanger, one 45 of the flanges of the bushing *l* may be made separate therefrom and attached thereto after the spool is placed on the bushing, or the spool itself may be divided longitudinally into sections which are glued or cemented together upon the bushing. The 50 ends of the loop *h*, which is made of malleable iron or bendable metal, are primarily spread to permit the insertion of the spool *k* with its bushing *l*, into place between the 55 pintles *i*, which are then forced into the ends of the bore or hole of the bushing.

The shank of the member *b* is formed with an eye *m*, which is fitted on the central downwardly curved bearing portion *j* of the 60 hanger loop, and is adapted to swing freely sidewise, as well as forward and backward thereon. At the rear side of the bearing portion *j*, the loop *h* is formed with an upwardly projecting stop lug *n*, to prevent the 65 eye *m* from being shifted backward out of proper position on said bearing portion and chafing the breast strap *a*.

The bight of the hook *d* is formed opposite its upwardly bent point with a notch *o*, 70 with which the eye *g* engages when it is held in normal position on said hook, as shown in Figs. 2 and 3.

A notch *p*, formed in one side of the eye *g*, registers with the notch *o* in the hook, 75 when the eye is turned sidewise into abnormal position, thereby permitting the eye to be placed on and removed from the hook *d*. In its normal position the eye *g* projects over the point of the neck yoke hook *c* and 80 closes the entrance to its bight, as shown in Figs. 1 and 3, thereby locking said hook in engagement with the neck yoke ring or loop *e*. To prevent the eye *g* from tipping sidewise 85 away from the hook *c*, and accidentally releasing it from engagement with the ring or eye *e*, the hook *d* is formed on the opposite side with a lug *q*. The shank of the eye *g* is formed with a loop for the attachment of the martingale *f* and the cross bar *r* of the 90 loop around which the martingale *f* is looped and stitched or otherwise permanently fastened, is formed with a tongue *s* and at the ends with guard flanges *t*, which 95 prevent the martingale from turning on and 100

55 60 65 70 75 80 85 90 95 100 105 110

shifting lengthwise of the cross bar *r*. Rubbing, abrupt bending and wear of the martingale where it is connected with the metal fastening, are thus avoided. The ring or loop *e* may be formed, as shown in Figs. 1 and 2, integral with a metal reinforcing sleeve or collar *u*, with which the end of the neck yoke is provided.

The fastening is manipulated as follows:

- 10 To connect it with a neck yoke, the breast strap *a*, being fastened at both ends and the hanger suspended therefrom, the hook *c* as seen in Fig. 1, is turned to the right, and the ring or loop *e* on the neck yoke is lifted into engagement therewith. The hook is then released and permitted to assume its normal working position, as shown in the drawing. The eye *g* of the martingale is then placed in position on the hook *d*, being turned for this purpose till the notch *p* is brought opposite the shank of the hook. After it has passed into place in the bight of the hook, the eye is turned back into its normal working position, thereby carrying its rim into engagement with the notch *o*, as shown in Fig. 2. The martingale thus connected with the hame strap and with the neck yoke, locks the fastening, closing the entrance into the bight of the hook *c* and preventing accidental disengagement of said hook from the ring or loop *e* of the neck yoke, as well as the accidental detachment of the martingale from the hook *d*.
- 35 To unhitch the breast strap and martingale from each other and from the neck yoke, the shank of the eye *g* is grasped and turned inwardly toward the center of the neck yoke till the notch *p* registers with the notch *o*, and the eye, thus released, is removed from the hook *b*, thereby unlocking the hook *c*, which is disengaged from the ring or loop *e* by lifting the neck yoke and swinging the hook inwardly on its bearing *j*, from which it is pivotally suspended.
- 40 45 Various changes in the minor details of construction and arrangement of parts of the device may be made without departure from the principle and scope of the invention as defined in the following claims.

50 I claim:

1. In a neck yoke fastening, the combination of a hook member adapted for connection with a breast strap and for detachable engagement with a neck yoke, and a martingale member rotatably fitting on said hook member and having a notch registerable in abnormal position with a projecting part of the hook member, the martingale member being locked in normal position by said projecting part and closing the entrance into the hook member.
2. In a neck yoke fastening, the combination of a breast strap hanger, a member articulated therewith and formed with a hook for detachable engagement with a neck yoke

ring or eye, and a martingale connecting member detachably engageable with said hook member and adapted when in normal engagement therewith to lock said hook in engagement with the neck yoke ring or eye. 70

3. In a neck yoke fastening, the combination of a breast strap hanger, a hook member articulated therewith and formed with two hooks arranged substantially at right angles to each other, a notch being formed 75 in the bight of one hook opposite its point, and an eye fitting over the notched hook into engagement with the notch therein and having a notch in one side registering in abnormal position of the eye with the notch in the hook, the eye being locked in its normal position on one hook and closing the entrance into the bight of the other hook.

4. In a neck yoke fastening, the combination of a breast strap hanger, a double hook 85 articulated therewith and having two upwardly bent points at approximately right angles to each other, one hook having a notch in the bight opposite the point, and a martingale eye fitting over the point of 90 the notched hook into engagement with the notch therein, and having a notch in one side registering in abnormal position with the notch in the hook to permit engagement and disengagement of the eye and hook, the eye being locked in its normal position on the notched hook and closing the entrance into the bight of the other hook, and the notched hook being formed on the side opposite the point of the other hook with a lug 100 adapted to prevent the eye from tipping away from said point.

5. In a neck yoke fastening, the combination of a hook member adapted for connection with a breast strap and for detachable 105 engagement with a neck yoke, and a martingale member rotatably fitting on said hook member and shiftable when turned sidewise into abnormal position on the hook member to open and close the entrance into the hook, one of said members having a notch and the other a projection registerable with the notch when the martingale member is turned sidewise into abnormal position.

6. In a neck yoke fastening, the combination of a hanger adapted to be suspended on a breast strap in a plane transverse to the length of the strap and comprising a metal loop having a central downwardly and sharply curved bearing portion of round 120 cross section with an inwardly projecting stop lug on the rear side thereof, and a hook formed with an eye fitting and free to turn sidewise and forward and backward on said bearing portion of the hanger loop and normally held in place thereon by said stop projection.

7. In a neck yoke fastening, the combination of a hanger, a double hook pivotally suspended thereon, and an eye detachably 130

fitted on one of the hooks and adapted in
normal position to be locked thereon and to
close the entrance into the bight of the other
hook, the shank of the eye being provided
5 with a cross bar formed with a tongue and
with guard flanges for the attachment of the
looped end of the martingale.

In witness whereof I hereunto affix my
signature in presence of two witnesses.

JAMES M. WALSH.
